RIVET BUCKING GUN

James H. Sargent, Clarence W. Harmon, Joseph R. Harmon, Marvin Elwood Harmon, Howard H. Harmon, James H. Sargent, Jr., and Joseph L. Sargent, Amonate, Va.

Application July 19, 1948, Serial No. 39,436

1 Claim. (Cl. 78—53.5)

1

This invention appertains to novel and useful improvements in devices for use in riveting.

An object of this invention is to back a rivet while riveting operations proceed through the medium of a tool which includes a sleeve having a bore and a counterbore with a plunger in the bore and an inertia member in the counterbore and three springs involved, two of which have relatively different compressive capacities engaging the inertia member while the other reacts on the end of the sleeve and a flange on the plunger.

Other objects and features of novelty will become apparent to those skilled in the art, and following the description of the preferred form of the invention, illustrated in the accompanying drawings, wherein:

Figure 1 is a sectional view of the preferred form of the invention;

Figure 2 is a sectional view taken on the line 2—2 of Figure 1 in the direction of the arrows;

Figure 3 is a sectional view taken substantially on the line 3—3 of Figure 1 in the direction of the arrows; and

Figure 4 is a transverse sectional view taken on the line 4—4 of Figure 1 in the direction of the arrows.

This invention has been developed in order to provide an improved device for bucking rivets and the like during the operation of applying the rivets wherever it is found desirable.

A sleeve 10 is provided with a bore 12 and a counterbore 14. An inertia member 16 is slidably received in the counterbore 14 and means for resiliently biasing the said inertia member is provided.

The preferred means consists of a relatively heavy spring 18 which engages a closure generally indicated at 20 and reacts on the inertia member 16. A secondary spring 22 is concentric with the relatively heavy spring 18 and is of lighter compressive characteristics. This last-mentioned spring 22 also engages the closure 20 and reacts on the inertia member 16. An aperture 24 is provided at one end of the inertia member in order to seat the pertinent end of the spring 22 therein.

The said closure 20 has an opening therein and a plurality of threads in the interior of the opening. Complemental threads 28 are provided on

the exterior of the closure 20 and the threads 28 and 28' are in engagement with the threads 28 and 28' respectively. The sleeve 10 has a shoulder 30 at the outer end of the bore 12 and a shoulder 32 at the outer end of the counterbore 14. A plunger 38 is received in the bore 12 and has an end 40 which is enlarged and has a groove 42 extending therearound. A spring 48 is interposed between the end of the sleeve 10 and the enlargement 40 of the plunger 38. A bucking recess 46 is provided in the end of the plunger 38.

The sleeve 10 has a shoulder 30 at the outer end of the bore 12 and a shoulder 32 at the outer end of the counterbore 14. A plunger 38 is received in the bore 12 and has an end 40 which is enlarged and has a groove 42 extending therearound. A spring 48 is interposed between the end of the sleeve 10 and the enlargement 40 of the plunger 38. A bucking recess 46 is provided in the end of the plunger 38.

The sleeve 10 has a shoulder 30 at the outer end of the bore 12 and a shoulder 32 at the outer end of the counterbore 14. A plunger 38 is received in the bore 12 and has an end 40 which is enlarged and has a groove 42 extending therearound. A spring 48 is interposed between the end of the sleeve 10 and the enlargement 40 of the plunger 38. A bucking recess 46 is provided in the end of the plunger 38.

The sleeve 10 has a shoulder 30 at the outer end of the bore 12 and a shoulder 32 at the outer end of the counterbore 14. A plunger 38 is received in the bore 12 and has an end 40 which is enlarged and has a groove 42 extending therearound. A spring 48 is interposed between the end of the sleeve 10 and the enlargement 40 of the plunger 38. A bucking recess 46 is provided in the end of the plunger 38.

The sleeve 10 has a shoulder 30 at the outer end of the bore 12 and a shoulder 32 at the outer end of the counterbore 14. A plunger 38 is received in the bore 12 and has an end 40 which is enlarged and has a groove 42 extending therearound. A spring 48 is interposed between the end of the sleeve 10 and the enlargement 40 of the plunger 38. A bucking recess 46 is provided in the end of the plunger 38.

The sleeve 10 has a shoulder 30 at the outer end of the bore 12 and a shoulder 32 at the outer end of the counterbore 14. A plunger 38 is received in the bore 12 and has an end 40 which is enlarged and has a groove 42 extending therearound. A spring 48 is interposed between the end of the sleeve 10 and the enlargement 40 of the plunger 38. A bucking recess 46 is provided in the end of the plunger 38.

The sleeve 10 has a shoulder 30 at the outer end of the bore 12 and a shoulder 32 at the outer end of the counterbore 14. A plunger 38 is received in the bore 12 and has an end 40 which is enlarged and has a groove 42 extending therearound. A spring 48 is interposed between the end of the sleeve 10 and the enlargement 40 of the plunger 38. A bucking recess 46 is provided in the end of the plunger 38.

The sleeve 10 has a shoulder 30 at the outer end of the bore 12 and a shoulder 32 at the outer end of the counterbore 14. A plunger 38 is received in the bore 12 and has an end 40 which is enlarged and has a groove 42 extending therearound. A spring 48 is interposed between the end of the sleeve 10 and the enlargement 40 of the plunger 38. A bucking recess 46 is provided in the end of the plunger 38.

The sleeve 10 has a shoulder 30 at the outer end of the bore 12 and a shoulder 32 at the outer end of the counterbore 14. A plunger 38 is received in the bore 12 and has an end 40 which is enlarged and has a groove 42 extending therearound. A spring 48 is interposed between the end of the sleeve 10 and the enlargement 40 of the plunger 38. A bucking recess 46 is provided in the end of the plunger 38.

The sleeve 10 has a shoulder 30 at the outer end of the bore 12 and a shoulder 32 at the outer end of the counterbore 14. A plunger 38 is received in the bore 12 and has an end 40 which is enlarged and has a groove 42 extending therearound. A spring 48 is interposed between the end of the sleeve 10 and the enlargement 40 of the plunger 38. A bucking recess 46 is provided in the end of the plunger 38.

The sleeve 10 has a shoulder 30 at the outer end of the bore 12 and a shoulder 32 at the outer end of the counterbore 14. A plunger 38 is received in the bore 12 and has an end 40 which is enlarged and has a groove 42 extending therearound. A spring 48 is interposed between the end of the sleeve 10 and the enlargement 40 of the plunger 38. A bucking recess 46 is provided in the end of the plunger 38.

The sleeve 10 has a shoulder 30 at the outer end of the bore 12 and a shoulder 32 at the outer end of the counterbore 14. A plunger 38 is received in the bore 12 and has an end 40 which is enlarged and has a groove 42 extending therearound. A spring 48 is interposed between the end of the sleeve 10 and the enlargement 40 of the plunger 38. A bucking recess 46 is provided in the end of the plunger 38.

The sleeve 10 has a shoulder 30 at the outer end of the bore 12 and a shoulder 32 at the outer end of the counterbore 14. A plunger 38 is received in the bore 12 and has an end 40 which is enlarged and has a groove 42 extending therearound. A spring 48 is interposed between the end of the sleeve 10 and the enlargement 40 of the plunger 38. A bucking recess 46 is provided in the end of the plunger 38.

The sleeve 10 has a shoulder 30 at the outer end of the bore 12 and a shoulder 32 at the outer end of the counterbore 14. A plunger 38 is received in the bore 12 and has an end 40 which is enlarged and has a groove 42 extending therearound. A spring 48 is interposed between the end of the sleeve 10 and the enlargement 40 of the plunger 38. A bucking recess 46 is provided in the end of the plunger 38.

The sleeve 10 has a shoulder 30 at the outer end of the bore 12 and a shoulder 32 at the outer end of the counterbore 14. A plunger 38 is received in the bore 12 and has an end 40 which is enlarged and has a groove 42 extending therearound. A spring 48 is interposed between the end of the sleeve 10 and the enlargement 40 of the plunger 38. A bucking recess 46 is provided in the end of the plunger 38.

The sleeve 10 has a shoulder 30 at the outer end of the bore 12 and a shoulder 32 at the outer end of the counterbore 14. A plunger 38 is received in the bore 12 and has an end 40 which is enlarged and has a groove 42 extending therearound. A spring 48 is interposed between the end of the sleeve 10 and the enlargement 40 of the plunger 38. A bucking recess 46 is provided in the end of the plunger 38.

The sleeve 10 has a shoulder 30 at the outer end of the bore 12 and a shoulder 32 at the outer end of the counterbore 14. A plunger 38 is received in the bore 12 and has an end 40 which is enlarged and has a groove 42 extending therearound. A spring 48 is interposed between the end of the sleeve 10 and the enlargement 40 of the plunger 38. A bucking recess 46 is provided in the end of the plunger 38.

The sleeve 10 has a shoulder 30 at the outer end of the bore 12 and a shoulder 32 at the outer end of the counterbore 14. A plunger 38 is received in the bore 12 and has an end 40 which is enlarged and has a groove 42 extending therearound. A spring 48 is interposed between the end of the sleeve 10 and the enlargement 40 of the plunger 38. A bucking recess 46 is provided in the end of the plunger 38.

The sleeve 10 has a shoulder 30 at the outer end of the bore 12 and a shoulder 32 at the outer end of the counterbore 14. A plunger 38 is received in the bore 12 and has an end 40 which is enlarged and has a groove 42 extending therearound. A spring 48 is interposed between the end of the sleeve 10 and the enlargement 40 of the plunger 38. A bucking recess 46 is provided in the end of the plunger 38.

The sleeve 10 has a shoulder 30 at the outer end of the bore 12 and a shoulder 32 at the outer end of the counterbore 14. A plunger 38 is received in the bore 12 and has an end 40 which is enlarged and has a groove 42 extending therearound. A spring 48 is interposed between the end of the sleeve 10 and the enlargement 40 of the plunger 38. A bucking recess 46 is provided in the end of the plunger 38.

Having described the invention, what is claimed as new is:

A tool comprising a sleeve having a bore and a counterbore communicating therewith to thereby form a shoulder at their junction, a plunger in said bore, an inertia member slidably disposed in said counterbore and adapted to engage said shoulder to limit the movement of the member, a closure, means for securing said closure directly to said sleeve at the end of said counterbore and 10 a part of said closure engaging the outer surface of said sleeve, a relatively heavy spring seated on said closure and reacting on said inertia member, and a relatively light spring seated on said closure and reacting on said inertia member, said plunger having an enlargement at one end thereof forming a flange, the opposite end contacting said inertia member, a spring seating on the end of the sleeve at the end of said bore and reacting

on said flange, and said plunger having a groove therein to inhibit spreading of the material of said plunger occasioned by shock.
